United States Patent Office

Des. 204,846
Patented May 17, 1966

204,846

WAFFLE COOKING PLATE

David Charles De Jersey, 231 Boundary Road,
East Bentleigh, Victoria, Australia

Filed Jan. 28, 1965, Ser. No. 83,615

Claims priority, application Australia Aug. 3, 1964

Term of patent 14 years

(Cl. D81—10)

FIG. 1 is a front perspective view from above of a waffle cooking plate according to my new design;

FIG. 2 is a rear perspective view from below of said waffle cooking plate;

FIG. 3 is a cross-sectional view taken at lines 3—3 of FIG. 1; and

FIG. 4 is an end view of said waffle cooking plate.

I claim:

The ornamental design for a waffle cooking plate, substantially as shown.

References Cited by the Examiner

UNITED STATES PATENTS

389,602	9/1888	Sankey	-----	99—445
1,446,532	2/1923	Wolcott	-----	99—340

FOREIGN PATENTS

580,305 8/1924 France.

WALLACE R. BURKE, Primary Examiner.

J. PAUL GUERTIN, Assistant Examiner.